UNITED STATES PATENT OFFICE

2,458,894

LOW-TEMPERATURE REFRIGERATION
SYSTEM

Samuel C. Collins, Cambridge, Mass., assignor, by
mesne assignments, to Arthur D. Little, Inc.,
Cambridge, Mass., a corporation of Massachusetts

Application October 14, 1940, Serial No. 361,137

14 Claims. (Cl. 62—178)

1

The invention relates to a refrigeration system for the production of low temperatures and is particularly directed to a low temperature refrigeration system involving the expansion of compressed gases with the performance of external work to produce low temperatures and to novel elements of such a system whereby low temperatures of the order of the temperature of liquid air and lower may be produced.

A principal object of the invention is the provision of a highly efficient refrigeration system for the production of low temperatures by the expansion of compressed gases with the performance of external work.

A further object of the invention is the provision of a low temperature refrigeration system involving the expansion of compressed gases with external work in which at least the low temperature portion of the system including the machine for expansion of the compressed gases is hermetically sealed.

Other objects and advantages of the invention will appear from the following description of the invention.

The low temperature refrigeration system of the invention is based upon the production of low temperatures by the expansion of compressed gases with the performance of external work. In order to make available the lowest temperatures helium is preferably utilized as the refrigerant medium, although the principles of the invention may be applied to systems utilizing other gases of relatively low boiling points as refrigerants.

In its preferred form the low temperature refrigeration system of the invention comprises:

A compressor;

A heat exchanger;

An expansion engine comprising a chamber hermetically sealed against the surrounding atmosphere and including a member movable by the expansion of compressed gas in the chamber and force-transmitting means operatively connected to the movable member;

A conduit for conveying compressed gas from the compressor through the heat exchanger to the chamber of the expansion engine;

A conduit for conveying expanded gas from the chamber to the space to be cooled; and

A conduit for conveying the gas from the cooled space to the compressor through the heat exchanger.

In the accompanying drawings:

Fig. 1 is a diagrammatic representation of a system for the production of low temperatures in

2

accordance with the principles of the invention, shown, for the purpose of illustration, as applied to the production of liquid oxygen from air; and

Fig. 2 is a diagrammatic representation of a further embodiment of the principles of the invention in a refrigerating system applied, for the purpose of illustration, to the production of liquid helium.

In the refrigeration system shown in Fig. 1, 10 and 11 are compression engines which are equipped with suitable means for removing heat of compression, such as coolers 10^a and 11^a, and are advantageously either of the floating piston type or the diaphragm type described herein, 12, 13 and 14 are expansion engines of either the floating piston type or the diaphragm type, and 15 and 16 are heat interchangers, preferably of the form described herein. Shown as an illustrative example of the utility of the system is rectifying column 17 for the production of liquid oxygen from air.

Helium is compressed to 30 atmospheres in compressor 10 and air is compressed to 5 atmospheres in compressor 11. After cooling, if necessary, to about 25° C. the compressed air and a portion of the compressed helium are passed successively through heat interchangers 15 and 16 in countercurrent heat exchange relation with the cold gaseous nitrogen from the rectifier and with portions of cold expanded helium.

A portion of the helium at 30 atmospheres pressure from compressor 10 is expanded in engine 12 with performance of work to a pressure of 2 atmospheres thereby reducing its temperature to about —100° C. This portion of expanded helium is returned to the compressor through heat exchanger 15 counter-current to the flow of compressed helium and air.

A further portion of the compressed helium at approximately —100° C. coming from interchanger 15 is expanded in engine 13 with performance of work to a pressure of 2 atmospheres thereby further reducing its temperature to about —175° C. This second portion of expanded helium is returned to compressor 10 through heat interchangers 16 and 15 successively. The remainder of the compressed helium leaving heat interchanger 16 at a temperature of about —175° C. is expanded in engine 14 to 2 atmospheres pressure and a temperature of about —220° C.

In the embodiment of the invention illustrated, this final low temperature helium is utilized for the production of liquid oxygen by passing it through condensing coil 18 in rectifying column 17, wherein it serves to condense nitrogen for re-

flux purposes in the column. Air under 5 atmospheres pressure which has passed successively through interchangers 15 and 16 is partially liquefied in the coil at the base of the rectifying column, thereby evaporating liquid oxygen surrounding the coil and providing gaseous oxygen which ascends the column in counterflow with descending liquid mixtures. The partially liquefied stream of air is expanded through reducing valve 19 to atmospheric pressure and passed into the middle of the column at approximately the boiling point of liquid air. The expanded helium from coil 18 returns to compressor 10 through heat interchangers 16 and 15 successively. The liquid oxygen fraction collects in the lower portion of the rectifying column. The gaseous nitrogen fraction from the top of the column is returned to the atmosphere through heat interchangers 15 and 16 in counter-current heat exchange relation to the compressed helium and air.

The temperature of -196° obtained by the refrigeration system shown in Fig. 1 is by no means a limiting temperature, since by increasing the number of stages of expansion and heat interchange, temperatures approaching the normal boiling point of liquid helium may be attained. Since the refrigerative effect, $H_1 - H_2$, of the expansion with performance of external work is given by the equation

$$H_1 - H_2 = \frac{\gamma}{\gamma-1} \left[1 - \left(\frac{P_2}{P_1} \right)^{\frac{\gamma-1}{\gamma}} \right] RT_1$$

per mol of ideal gas, where

$$\gamma = \frac{C_p}{C_v}$$

is the ratio of the heat capacity for constant pressure to that for constant volume, P_1 =initial pressure and P_2 =final pressure, it is evident that with a given quantity of gas expanding from P_1 to P_2 the amount of refrigeration is proportional to the absolute temperature of the admitted charge of gas.

Since the expansion of compressed gas with the performance of work is an essential feature of the refrigeration system of the invention it is obvious that the successful and efficient performance of the system depends in very large part upon the engine used for the expansion.

As an example of the utilization of the refrigeration system of the invention, for the production of temperatures below the boiling point of liquid oxygen, Fig. 2 is a diagrammatic representation of a system utilizing the principles of the invention for the production of liquid helium.

In Fig. 2, 150 is the compressor of the refrigerating system, which may be, for example, a floating piston engine, although conventional compressors may be used. 151 is a conventional cooling device. 152, 153, 154, 155, 156 and 157 are interchangers. 158 and 159 are expansion engines. 160 is an expansion valve. 161 is a reservoir for low pressure helium and 162 is a purifying reservoir.

163 is a source of gaseous helium to be liquefied, for example, a conventional pressure cylinder and 164 is the liquid helium chamber.

The low temperature elements of the system are surrounded by radiation shield 165. The interior of the chamber formed by the radiation shield 165 or of the walls of the shield is evacuated.

Helium is compressed to 15 atmospheres by compressor 150 and cooled to 30° C. in cooler 151. A portion, approximately four-fifths, of this

helium is cooled to -200° C. in heat interchanger 153, and a portion of this helium at -200° C. and 15 atmospheres pressure is expanded in engine 158 to provide helium at about -225° C., part of which is used to cool helium to be liquefied to about -200° C. in interchanger 152 and part of which is utilized to maintain radiation shield 165 at -200° C. or below and to remove a portion of the heat from the compressed helium passing through interchanger 153.

The remaining portion of the compressed helium at -200° C. from interchanger 153 is cooled to about -253° C. in interchanger 154 and is then expanded in engine 159 to provide helium at about -261° C. for cooling interchanger 156 and interchanger 154 in succession.

20 A purifier 162 is preferably placed in this portion of the system at the point of lowest temperature of the compressed helium between interchanger 154 and engine 159. In purifier 162 the helium is caused to pass through a layer of charcoal 167. By placing the charcoal chamber at this point impurities are very effectively removed from the helium and the helium in the refrigeration system is constantly maintained at a very high degree of purity.

The remaining one-fifth of the compressed helium at 30° C. from cooler 151 is passed successively through interchangers 155, 156 and 157 30 wherein it is cooled successively to -248° C., -261° C. and -264° C. It is then expanded through valve 160 into the cooling coil 166 of liquefier 164. At this expansion the temperature falls to about -268° C. Liquid helium is produced 35 during the expansion but it evaporates in coil 166 because of the condensation of helium in liquefier 164 at a slightly higher pressure. The cold low pressure helium from coil 166 flows back to compressor 150 through interchangers 157, 156 and 40 155 in succession. The helium to be liquefied coming from interchanger 152 is further cooled to -261° C. in interchanger 156 before passing to the liquefier.

45 The expanded gas leaving interchanger 156, instead of being used for the production of liquid helium inside the vacuum chamber, as shown in Fig. 2, may be led outside the chamber to any point where low temperature refrigeration is desired.

50 I claim:

1. A low temperature gas cycle refrigeration system comprising a compressor, a plurality of heat exchangers, a plurality of expansion engines 55 for the expansion of compressed gas with the performance of external work each comprising a chamber hermetically sealed against leakage to and from the surrounding atmosphere and including a member movable by the expansion of compressed gas in the chamber and force transmitting means operatively connected to the movable member, conduit means for conveying a portion of the compressed gas from the compressor through a plurality of said heat exchangers in 60 succession and to one of said expansion engines, conduit means for conveying further portions of said compressed gas from at least one point prior to its passage through the last of said successive heat exchangers to further of said expansion engines, and conduit means for conveying expanded gas from said further expansion engines through said heat exchangers to said compressor counter-current to the flow of said compressed gas, conduit means for conveying said first portion 65 of expanded gas to a space to be cooled, and 70 engines, and conduit means for conveying expanded gas from said further expansion engines through said heat exchangers to said compressor counter-current to the flow of said compressed gas, conduit means for conveying said first portion 75 of expanded gas to a space to be cooled, and

conduit means for conveying the gas from the cooled space to the compressor through said heat exchangers counter-current and in inverse order to the flow of said compressed gas.

2. A low temperature gas cycle refrigeration system comprising a compressor, two heat exchangers, three expansion engines for the expansion of compressed gas with the performance of external work each comprising a chamber hermetically sealed against leakage to and from the surrounding atmosphere and including a member movable by the expansion of compressed gas in the chamber and force transmitting means operatively connected to the movable member, conduit means for conveying a portion of the compressed gas from the compressor through said heat exchangers in succession, conduit means for conveying a further portion of said compressed gas from said compressor to one of said expansion engines, conduit means for conveying the expanded gas from said first engine to said compressor through the first heat exchanger counter-current to the flow of the compressed gas therethrough, conduit means for conveying a portion of the compressed gas leaving said first heat exchanger to the second of said expansion engines, conduit means for conveying expanded gas from said second engine through said heat exchangers counter-current and in inverse order to the flow of said compressed gas, conduit means for conveying the remaining portion of the compressed gas from the second of said heat exchangers to the third of said expansion engines, conduit means for conveying expanded gas from said third expansion engine to a space to be cooled, and conduit means for conveying the gas from the cooled space to the compressor through said heat exchangers counter-current and in inverse order to the flow of said compressed gas.

3. A low temperature gas cycle refrigeration system comprising a compressor, a heat exchanger, an expansion engine for the expansion of compressed gas with performance of external work, a second heat exchanger, a second expansion engine for the expansion of compressed gas with performance of external work, conduit means for conveying a portion of the compressed gas from the compressor through said first heat exchanger to said first expansion engine, conduit means for conveying expanded gas from said first expansion engine through said first heat exchanger counter-current to the flow of compressed gas therethrough, conduit means for conveying a further portion of the compressed gas successively through said first and second heat exchangers to said second expansion engine, conduit means for conveying expanded gas from said second expansion engine through a space to be cooled and thereafter successively through said second and said first heat exchangers counter-current to the flow of compressed gas therethrough.

4. A low temperature gas cycle refrigeration system comprising a compressor, a plurality of heat exchangers, a plurality of expansion engines for the expansion of compressed gas with the performance of external work, conduit means for conveying a portion of the compressed gas from the compressor through a plurality of said heat exchangers in succession and to one of said expansion engines, conduit means for conveying further portions of said compressed gas from at least one point prior to its passage through the last of said successive heat exchangers to other

expansion engines, and conduit means for conveying expanded gas from said other expansion engines through said heat exchangers to said compressor counter-current to the flow of said compressed gas, conduit means for conveying said first portion of expanded gas through a space to be cooled, and conduit means for conveying the gas from the cooled space to the compressor through said heat exchangers counter-current

10 and in inverse order to the flow of said compressed gas.

5. A low temperature gas cycle refrigeration system comprising a compressor, two heat exchangers, three expansion engines for the expansion of compressed gas with the performance of external work, a conduit for conveying a portion of the compressed gas from the compressor through said heat exchangers in succession, conduit means for conveying a further portion of said compressed gas from said compressor to one of said expansion engines, conduit means for conveying the expanded gas from said first engine to said compressor through the first of said heat exchangers counter-current to the flow of the compressed gas therethrough, conduit means for conveying a portion of the compressed gas leaving said first of said heat exchangers to the second of said expansion engines, conduit means for conveying expanded gas from said second engine through said heat exchangers counter-current and in inverse order to the flow of said compressed gas, conduit means for conveying the remaining portion of the compressed gas from the second of said heat exchangers to the third of said expansion engines, conduit means for conveying expanded gas from said third expansion engine through a space to be cooled, and conduit means for conveying the gas from the cooled space to the compressor through said heat exchangers counter-current and in inverse order to the flow of said compressed gas.

6. A low temperature gas cycle refrigeration system comprising a first heat exchanger, a main conduit for conducting a compressed gas through said first heat exchanger, a first expansion engine for expanding compressed gas with the performance of external work, a first branch conduit connected with said main conduit after passing through said first heat exchanger for conducting a portion of the compressed gas to said first expansion engine, a first return conduit connected with said first expansion engine for conducting expanded gas through said first heat exchanger in heat exchange relation to said main conduit, a second expansion engine for expanding compressed gas with the performance of external work, a second heat exchanger, a second branch conduit connected with said main conduit after passing through said first heat exchanger for conducting another portion of compressed gas through said second heat exchanger and then to said second expansion engine, an exhaust conduit for conducting expanded gas from said second expansion engine to a space to be cooled, and a second return conduit for conducting the expanded gas from said space to be cooled through said second heat exchanger in heat exchange relation to said second branch conduit and then through said first heat exchanger in heat exchange relation to said main conduit.

7. A low temperature gas cycle refrigeration system comprising a heat shield defining an enclosure, a first heat exchanger and a second heat exchanger within said enclosure, an expansion engine, a duct in heat exchange relation with a

space to be cooled within said enclosure, said duct having an inlet provided with an expansion valve and an outlet, said expansion engine being operative to expand compressed gas with the performance of external work, a main conduit adapted to be connected with a source of compressed gas, said main conduit having a first branch and a second branch, said first branch being arranged to conduct a portion of compressed gas from said main conduit through said first heat exchanger and then to said expansion engine, an exhaust conduit for conducting the expanded gas from said expansion engine about said heat shield and then through said first heat exchanger in heat exchange relation to said first branch conduit, said second branch being arranged to conduct another portion of compressed gas from said main conduit through said second heat exchanger and then to said expansion valve, and a return conduit for conducting the expanded gas from the outlet of said duct through said second heat exchanger in heat exchange relation to said second branch.

8. A low temperature gas cycle refrigeration process which comprises dividing a continuous main stream of compressed gas into a first stream and a second stream of compressed gas, expanding said first stream of compressed gas with the performance of external work to produce a first stream of expanded gas, passing said first stream of expanded gas into heat exchange relation with said main stream of compressed gas, expanding said second stream of compressed gas with the performance of external work to produce a second stream of expanded gas, and passing said second stream of expanded gas successively into heat exchange relation with a space to be cooled, with said second stream of compressed gas and with said main stream of compressed gas.

9. A low temperature gas cycle refrigeration process which comprises dividing a continuous main stream of compressed gas into a first stream and a second stream of compressed gas, expanding said first stream of compressed gas with the performance of external work to produce a first stream of expanded gas, passing said first stream of expanded gas into heat exchange relation with said second stream of compressed gas and with said main stream of compressed gas, expanding said second stream of compressed gas with the performance of external work to produce a second stream of expanded gas, and passing said second stream of expanded gas successively into heat exchange relation with a space to be cooled, with said second stream of compressed gas and with said main stream of compressed gas.

10. A low temperature gas cycle refrigeration process which comprises dividing a continuous main stream of compressed gas into a first stream and a second stream of compressed gas, expanding said first stream of compressed gas with the performance of external work to produce a first stream of expanded gas, passing said first stream of expanded gas into heat exchange relation with said second stream of compressed gas, dividing said second stream of compressed gas into a third stream and a fourth stream of compressed gas, expanding said third stream of compressed gas with the performance of external work to produce a second stream of expanded gas, passing said second stream of expanded gas successively into heat exchange relation with said fourth stream of compressed gas and with said second stream of compressed gas, expanding said fourth stream of compressed gas to produce a third stream of expanded gas, passing said third stream of expanded gas into heat exchange relation with said first stream of expanded gas, and passing said third stream of expanded gas into heat exchange relation with a space to be cooled, with said third stream of expanded gas and with said first stream of expanded gas.

5 stream of expanded gas, and passing said third stream of expanded gas successively into heat exchange relation with a space to be cooled, with said fourth stream of compressed gas and with said second stream of compressed gas.

11. A low temperature gas cycle refrigeration process which comprises dividing a continuous main stream of compressed gas into a first stream and a second stream of compressed gas, expanding said first stream of compressed gas with the performance of external work to produce a first stream of expanded gas, passing said first stream of expanded gas successively into heat exchange relation with a zone interposed between the ambient atmosphere and a space to be cooled and with said main stream of compressed gas, expanding said second stream of compressed gas to produce a second stream of expanded gas, and passing said second stream of expanded gas successively into heat exchange relation with the space to be cooled, with said second stream of compressed gas and with said main stream of compressed gas.

12. A low temperature gas cycle refrigeration process which comprises dividing a continuous main stream of compressed gas into a first stream and a second stream of compressed gas, dividing said first stream of compressed gas into a third stream and a fourth stream of compressed gas, expanding said third stream of compressed gas to produce a first stream of expanded gas, passing said first stream of expanded gas into heat exchange relation with said first stream of compressed gas, expanding said fourth stream of compressed gas to produce a second stream of expanded gas, passing said second stream of expanded gas successively into heat exchange relation with said second stream of compressed gas, with said fourth stream of compressed gas and with said first stream of compressed gas, expanding said second stream of compressed gas to produce a third stream of expanded gas, and passing said third stream of expanded gas successively into heat exchange relation with a space to be cooled and with said second stream of compressed gas.

13. A low temperature gas cycle refrigeration process which comprises dividing a continuous main stream of compressed helium into a first stream and a second stream of compressed helium, expanding said first stream of compressed helium with the performance of external work to produce a first stream of expanded helium, passing said first stream of expanded helium into heat exchange relation with said main stream of compressed helium, expanding said second stream of compressed helium to produce a second stream of expanded helium, passing said second stream of expanded helium successively into heat exchange relation with a space to be cooled, with said second stream of compressed helium and with said main stream of compressed helium, and causing said first stream of expanded helium to pass, prior to passing it in heat exchange relation with said main stream of compressed helium, between said second stream of expanded helium and said space to be cooled, on the one hand, and the ambient atmosphere, on the other hand.

14. A low temperature gas cycle refrigeration process which comprises dividing a continuous main stream of compressed helium into a first stream and a second stream of compressed helium, expanding said first stream of compressed helium with the performance of external work

to produce a first stream of expanded helium, passing said first stream of expanded helium into heat exchange relation with said second stream of compressed helium, dividing said second stream of compressed helium into a third stream and a fourth stream of compressed helium, expanding said third stream of compressed helium with the performance of external work to produce a second stream of expanded helium, passing said second stream of expanded helium successively into heat exchange relation with said fourth stream of compressed helium and with said second stream of compressed helium, expanding said fourth stream of compressed helium to produce a third stream of expanded helium, and passing said third stream of expanded helium successively into heat exchange relation with a space to be cooled, with said fourth stream of compressed helium and with said second stream of compressed helium.
